WATER GUN

Irving Richardson, Newark, N. J.

Application April 16, 1948, Serial No. 21,377

5 Claims. (Cl. 222—79)

1

This invention relates to mechanical toys and more particularly to a toy machine gun for ejecting water.

It is among the objects of my invention to provide a toy machine gun for ejecting measured quantities of water, that is neat, compact and realistic in appearance and of light, rugged and inexpensive construction including the use substantially solely of only sheet metal and rod stock to simulate the appearance of a genuine machine gun, which has a large water capacity so that a relatively great number of individual charges of water may be ejected on one filling, that is easy to fill and operate, that may readily be assembled having but few moving parts that are not likely to get out of order and in use is not likely to cause injury to the user.

According to the invention, these objects are accomplished by the arrangement and combination of elements hereinafter described and particularly recited in the claims.

In the accompanying drawings in which are shown one of various possible embodiments of the several features of the invention,

Fig. 1 is a top elevation of the gun,

Fig. 2 is a side elevation thereof,

Fig. 3 is a fragmentary sectional view on a larger scale taken along line 3—3 of Fig. 1,

Fig. 4 is a transverse sectional view taken along line 4—4 of Fig. 3,

Fig. 5 is a longitudinal sectional view taken along line 5—5 of Fig. 3, and on a larger scale,

Fig. 6 is a transverse sectional view taken along line 6—6 of Fig. 3,

Fig. 7 is a sectional detail view taken along line 7—7 of Fig. 2 and

Fig. 8 is a sectional detail view on a larger scale taken along line 8—8 of Fig. 3.

Referring now to the drawings, the toy gun comprises a body 10 which is a casing composed of two complementary sheet metal stampings 11 and 12 each forming an outline which includes the stock 13, the chamber 14 and the grip 16.

The two complementary pieces are assembled by crimping the edge 17 of one about the angle formation 18 of the other to form a seam 19. One of the complementary pieces has a substantially rectangular aperture 21 therein providing access into the chamber 14. The edge of aperture 21 has a countersunk flange 22 unitary therewith on which a cover plate 23 may be seated so as to be flush with the surface of complementary piece 11. The cover plate 23 is affixed over the aperture by means of lugs 24 integral

2

with the edge of flange and extending through corresponding openings 25 in the cover plate.

The barrel 15 is made of a single piece of sheet metal, affixed to the forward edge of the body 10 as at 39 by a seam similar to that above described and shown in Fig. 8. The barrel is corrugated as at 26 to simulate cooling vanes and provided with side walls 27 unitary therewith and retained together by a closure plate 28 bridging across the lower and front edges of the side walls 27 of the barrel and secured thereto by tines or lugs 29 integral with said side walls and extending through openings 31 in said closure plate.

The muzzle 32 of the barrel extending beyond the front edges of the side walls 27, is formed into a cylinder by bending together the lower edges 35, the latter being retained together by means of washers 33 through which tines or lugs 34 on each of said lower edges 35 extend and which are bent over as shown in Fig. 6.

The front edge of the muzzle 32 has an annular groove 36 on the inner wall thereof, in which is seated a disc 37 securely retained in place when the muzzle is assembled as above described and which carries a nozzle 38 preferably of plastic and rigidly affixed in and extending through said disc at right angles thereto. As shown in Fig. 3, the nozzle 38 has a bore 30 therethrough in which is affixed a pipe 40 having a capillary channel or bore 40' therethrough and protruding from the inner end of the nozzle as at 76.

Positioned in the chamber 14 and extending longitudinally thereof, is a substantially cylindrical water tank 41 having a rounded top and bottom and elongated flattened sides and occupying substantially the entire chamber. The tank is retained in position by cross pins 42 extending through the body 10 of the gun at each end of and beneath the water tank. The latter has a filling aperture 43 in the top thereof, preferably near the front end as shown, and aligned with a port or opening 44 in the top of the gun. A removable plug 45 is provided which extends through port 44 into filling aperture 43 to seal the latter.

A water pump 48 is provided comprising a cylinder 49 positioned in the chamber 14 so as to extend longitudinally of the water tank and affixed to the bottom of the latter, preferably near the rear thereof as by soldering or welding. The pump has an inlet 47 in the top thereof, which is aligned with a discharge opening 46 in the bottom of the water tank, and an outlet 51 at the front end thereof. The rear end of the cylinder 49 is of enlarged diameter as at

50, forming a shoulder 52. Positioned in cylinder 49 is a piston 53 comprising a rubber cup 54 affixed to the reduced end 55 of a piston rod 56. End 55 extends through the cup and is headed as at 57 rigidly to clamp the cup between metal washer 58 which is seated on shoulder 59 of reduced end 55 and metal washer 61 seated in the hollow of the cup. A pair of metal washers 62 and 63 encompass the piston rod and sandwich a felt packing disc 64 therebetween, the latter being of slightly larger diameter than said washers, and the inner diameter of the enlarged portion 50 of the cylinder. The metal washers 62 and 63 and the felt disc 64 are positioned in the enlarged portion 50 of cylinder 49 with washer 63 seated on shoulder 52 thereof to make a water tight seal. A coil spring 65 encompasses said plunger rod 56 and is compressed between washer 62 and the cross piece 66 of a yoke 67 affixed to the free end of the piston rod 56. The piston rod 56 is of such length that with washer 63 seated against shoulder 52, the forward edge of rubber cup 54 will be of the rear of inlet 47 of the cylinder, thereby permitting water to flow freely therein from outlet 46 of the water tank.

A substantially rectangular actuating yoke or pitman 68 is provided, the side walls 69 of which straddle pump 48. A cross pin 71 is provided at the rear end of the pitman 68 which extends transversely through the side walls 69 thereof and through the side walls 72 of the yoke 67 affixed to the end of the piston rod. An aperture 73 is provided in the cross piece 74 at the front end of the pitman 68 through which a tube 75 extends, the latter being affixed at one end to the outlet end 51 of the water pump and extends through the chamber 14 and barrel 15, being affixed at its free end to the protruding end 76 of pipe 40 of nozzle 38.

In order to actuate the piston rod 56, a trigger or lever 77 is provided having a pair of upstanding arms 78 straddling the gun grip 16 and pivoted thereto as at 79. The upper ends 81 of arms 78 extend through the slots 82 in the chamber 14 and protrude between the side walls 69 of the pitman, straddling tube 75 and normally in engagement with the cross piece 74 of said pitman.

Assembly

The body of the gun is first assembled and the barrel affixed thereto with the lower edges 35 of the muzzle end thereof spaced from each other.

The water tank 41 with the pump 48 and pitman 68 affixed thereto is then inserted between the side walls 27 of the barrel into chamber 14. Cross pins 42 are then positioned through the body 10 at each end of and beneath the tank to hold the latter in place, one end of tube 75 being previously passed through aperture 73 in cross piece 74 and affixed to the outlet 51 of the pump.

The free end of the tube 75 is then affixed to nozzle 38 as at 76 and the disc 31 supporting the latter is positioned in annular groove 36. The bottom edges 35 of the muzzle are then brought together and the tines 34 thereof are inserted in washer 35 and bent over, securely to clamp the disc in place.

The arms 78 of trigger 77 are then inserted through openings 82 in chamber 14 so that the upper ends 81 are positioned between the side walls 69 of pitman 68 straddling tube 75. As

the aperture 21 in the body 10 is open, it is a simple matter properly to position ends 81 of trigger 77. The trigger is then pivoted to grip 16 by pin 79 and cover plate 23 is affixed over aperture 21 by tines 21 to complete the assembly.

Operation

To use the gun, it is merely necessary to fill the water tank with water through filling aperture 44 thereof and replace the closure plug 45 therein. Inasmuch as the compressed coil spring 65 retains the cup 54 to the rear of inlet 47 of the water pump 48, the latter will quickly be filled. When the user pulls the trigger or lever 77, the latter will pivot about pin 79 to force the upper ends 81 of arms 78 against cross piece 74, thereby moving the pitman forward and forcing piston rod 56 and cup 54 into the cylinder to force the water therein through outlet 51 and tube 75 and out of nozzle 38. When the trigger is released, the tension of compressed spring 65 will retract the piston rod and cup 54 to its normal position to the rear of inlet 47 and as the cross piece 74 of the pitman will press against the upper ends of arms 78, the trigger 77 will also be pivoted in readiness for the next ejection of water.

If access is desired to the pump mechanism which is the only moving part of the gun, it is only necessary to remove cover plate 23 from aperture 21 to afford free communication with the interior of the chamber.

As pipe 40 of nozzle 38 has a capillary bore 40' there is no danger of leakage therefrom if the gun should be held with its muzzle pointing downward. In addition after the trigger 77 has been pulled several times to initially discharge water from the nozzle 38, the tube 75 will remain filled with water due to such capillary pipe 40 and every subsequent pulling of the trigger 77 will cause a stream of water to be ejected without the need for squeezing the trigger several times to charge the tube 75.

As the diameter of the capillary bore 40' is much less than that of tube 75, the pressure built up in the latter by the pulling of trigger 77 will cause the thin stream of water ejected from nozzle 38 to be propelled a relatively great distance.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A toy gun of the type comprising a body having a chamber therein, a barrel affixed to said body and extending longitudinally thereof, a water tank mounted in said chamber and extending longitudinally thereof, a pump in said chamber, in communication with said water tank and having a piston rod, resilient means normally retaining said piston rod in pump filling position, actuating means for said piston rod comprising a substantially rectangular frame affixed at one end to said piston rod, extending longitudinally of said pump and straddling the latter, and a lever operatively connected to the free end of said rectangular frame, pivoted to said body and extending from said chamber,

and a discharge nozzle affixed in said barrel at the front end thereof and in communication with said pump.

2. A toy gun of the type comprising a body having a chamber therein, a barrel affixed to said body and extending longitudinally thereof, a discharge nozzle affixed in the front end of said barrel, a water tank mounted in said chamber and extending longitudinally thereof, a pump in said chamber having an outlet, and an inlet in communication with said water tank, said pump having a piston rod, resilient means normally retaining said piston rod in pump filling position, actuating means for said piston rod, said means comprising a substantially rectangular frame affixed at one end to said plunger rod, extending longitudinally of said pump and straddling the latter, a tube connected at one end to the outlet of said pump, and at its other end to said nozzle, the front end of said rectangular frame having an opening through which said tube passes, and a lever pivoted to said body and having a pair of arms integral therewith and extending into said chamber between the sides of said rectangular frame and straddling said tube, the ends of said arms being operatively connected to the front end of said frame to actuate the latter.

3. The combination set forth in claim 2 in which said pump is rigidly affixed to the bottom of said water tank and extends longitudinally thereof.

4. A toy gun of the type comprising a body having a chamber therein, a barrel affixed to said body and extending longitudinally thereof, a discharge nozzle affixed in the front end of said barrel, a water tank mounted in said chamber extending longitudinally thereof and occupying substantially the entire volume thereof, a pump at the rear end of said chamber rigidly affixed to the bottom of said water tank and extending longitudinally thereof, said pump hav-

ing an outlet therefrom and an inlet in communication with said water tank, said pump having a piston rod, resilient means normally retaining said piston rod in pump filling position, actuating means for said piston rod, said means comprising a substantially rectangular frame affixed at one end to said plunger rod, extending longitudinally of said pump and straddling the latter, an elongated tube connected at one end to the outlet of said pump, extending longitudinally through said chamber and said barrel and connected at its other end to said nozzle, the front end of said rectangular frame having an opening through which said tube passes, and a lever pivoted to said body and having a pair of arms integral therewith and extending into said chamber adjacent the rear of said water tank, said arms extending between the sides of said rectangular frame and straddling said tube, the ends of said arms being operatively connected to the front end of said frame to actuate the latter.

5. The combination set forth in claim 4, in which said nozzle has a bore therethrough in which a pipe having a capillary bore is affixed, said pipe protruding from the bore of said nozzle at the inner end thereof and to which said tube is connected.

IRVING RICHARDSON.
